DISPLAY STAND

Emile Baldeck, Pully-Port, Lausanne,
SwitzerlandApplication March 3, 1936, Serial No. 66,916
In Switzerland September 11, 1935

1 Claim. (Cl. 211—134)

My invention relates to improvements in display-stands commonly used in show-windows and shops and in which—in an otherwise well-known manner—boards for the display of goods are interchangeably and at different elevations attached to a column which latter is provided with a footing.

Whereas in those designs of such columns which are known to the art the boards are fastened by way and means of a rod passing through the edges of said boards and through said column, which latter consists of individual parts between consecutive boards, said boards in the present invention are held between the two walls of slits accurately fitting, with the latter being arranged at different elevations in planes at right angles to the axis of said column and staggered with relation to each other.

The said arrangement results in the advantage that no screws have to be loosened for the dislocation of said boards and thus no tools will be required and, furthermore, there will not be any possibility that any parts of the stand become mislaid or lost.

In order now to afford a sure grip of said boards in said slits of the column, it is of course necessary that a material be used for the manufacturing of the latter and the boards which does not deform under the influence of changes of temperature and of the humidity of the atmosphere. Such materials are metals and the various artificial resins.

Since said arrangement of boards and column does away with the use of screws, clamps and the like, said boards may be removed, interchanged and attached in a very simple and rapid manner. The slight spring-like, yielding action of the column in the cross-sectional area remaining back of the notches or grooves required for the insertion of said boards is sufficient for exerting a clamping effect on the boards thus assuring a sufficient grip or hold for the latter.

In the accompanying drawing an execution of design is illustrated in the way of an example showing—

Figure 1, a side-view;
Fig. 2, a plan-view; and
Fig. 3, a perspective view of the stand.

1 is the foot-plate of the stand, consisting of a casting 3 with a sheet-iron covering 2. A pipe 4—forming the column proper—is attached to said foot-plate 1 and is provided with notches, grooves or incisions 5 at different elevations and staggered in horizontal planes about its circumference. Said notches extend up to, or even beyond, the axis of said column so that the remaining part of the cross-sectional area of the latter at these points of grooving allows a slight spring-like and yielding action of the top and bottom walls of said column.

Boards 6 now may be slid or introduced into said grooves in an accurately fitting way and manner and will be held there without the help of screws, clamps and the like.

It is understood that the cross-section of said column, instead of being circular, may have any form or shape and that the form of the foot-plate is adapted to the cross-section of the column.

The stand shown and described especially is adapted for the display of objects in show-windows. It may, however, also be used in households for displaying pots of flowers and the like.

An electric lamp may be attached to the upper end of column 4 for illuminating the articles displayed on the boards 6, whereby the wiring suitably is conducted inside the hollow column 4.

I claim:

A display stand including a hollow column, 30 the otherwise uninterrupted annular wall of which is formed with a series of channels opening through the surface thereof and off-set relative to each other vertically of the column, the channels being formed by incisions through the annular wall of the column to a depth approximating one-half the circumferential length of the annular wall of the column, each of the channels having a depth in such relation to the transverse dimension of the column as to permit a slight 35 yielding of that portion of the column above a particular channel under pressure against the upper and lower walls of the channel, whereby the channel may yield slightly to receive an element and clamp the element in the channel without additional fastening.

EMILE BALDECK.
